UNITED STATES PATENT OFFICE.

JOSEF MARTIN, OF MUNICH, GERMANY.

RECEPTACLE FOR LIGHT ASHES.

1,103,794.

Specification of Letters Patent. Patented July 14, 1914.

Application filed January 26, 1914. Serial No. 814,604.

To all whom it may concern:

Be it known that I, JOSEF MARTIN, a subject of the King of Bavaria, residing at Munich, Germany, have invented certain new and useful Improvements in Receptacles for Light Ashes, of which the following is a specification, reference being had therein to the accompanying drawing.

This invention relates to a receptacle for the dustless conveyance of light ashes and consists in the special construction of this receptacle with a displaceable side hopper and a conveyer screw.

The drawing illustrates a construction of the invention as follows: The receptacle *a* for carrying light ashes is suspended by the suspension device *b* from the traveling wheels of a mono-rail track. The filling opening of the receptacle is arranged at one side and is provided with a tubular projection *c* which by aid of the screw spindle *d* and the double armed lever *e* is displaceable in the vertical direction. The outlets of the hopper containing the light ashes are provided with frusto-conically shaped orifices *f*, which can be pressed close against the correspondingly shaped orifice of the tubular piece *c*. When the closing lid *g* is open, then the light ashes fall out of the hopper into the receptacle *a* and fill this latter up to the critical angle of flow of the ashes (indicated in the drawing by a dotted line). Hereupon, the closing lid *g* is shut and a carrier screw *h* placed in the receptacle is caused to revolve. By this means, the empty space within the receptacle is filled with the light ashes, enabling the ashes remaining in the tubular piece to slip down. After this, the tubular piece *c* is lowered until it is disengaged from the mouthpiece *f* of the hopper, and the receptacle can then be moved along the mono-rail.

By this construction of the receptacle, the advantage is attained that also the tubular piece which forms the filling hopper is dis-

charged within the receptacle, consequently any spilling over after the filling during the sinking of the tubular piece cannot take place.

Having now particularly described and ascertained the nature of my said invention and in what manner the same is to be performed, I declare that what I claim is:—

1. Means for the removal of light ashes, comprising a receptacle a suspending rod 55 connecting said receptacle to a track rail, a hopper above said receptacle a tube connecting said hopper to said receptacle, means to reciprocate said tube vertically and a conveyer in the upper part of said 60 receptacle.

2. A device for the dustless removal of light ashes comprising a receptacle suspended by a vertical hanger to a mono-rail, a hopper above said receptacle a main tube 65 connecting said hopper with said receptacle, a frusto-conical inlet to said tube contacting closely with a frusto-conical outlet on said hopper, a short tube on the opening into said receptacle into which the main 70 tube telescopes, a two-armed lever fulcrumed on said hanger and adapted to vertically reciprocate said main tube, a conveyer screw disposed transversely in the upper part of said receptacle, and means to 75 actuate said lever and said conveyer screw.

3. In a device for the removal of light ashes having a receptacle, a hopper above said receptacle and a main tube connecting said hopper to said receptacle, a short tube 80 making a telescoping joint with said main tube and means to vertically reciprocate said main tube, as specified.

In testimony whereof I have affixed my signature in the presence of two witnesses. 85

JOSEF MARTIN.
